UNITED STATES PATENT OFFICE.

ARTHUR R. THOMPSON, OF SAN FRANCISCO, CALIFORNIA, ASSIGNOR OF ONE-THIRD
TO MARY HUNT, OF SAN FRANCISCO, CALIFORNIA.

GAS-BURNER ATTACHMENT.

Application filed March 22, 1926. Serial No. 96,596.

This invention relates to improvements in gas burner attachments and has particular reference to a device for automatically shutting off the gas supply should the burner become extinguished.

Another object of this invention is to produce a device which is simple in construction and therefore cheap to manufacture.

Another object is to provide a device which may be readily attached to any gas burner.

Other objects and advantages will be apparent during the course of the following description.

15 In the accompanying drawings forming a part of this specification and wherein like numerals are employed to designate like parts throughout the same,

Figure I is a top plan view of a gas burner having my device attached thereto,

Figure II is a vertical cross-section of the sliding latch,

Figure III is a fragmentary view similar to Figure II, showing the latch in locked position, and

Figure IV is an end elevation of the latch box showing the latch in its two positions.

Many people have been asphyxiated through a gas burner becoming extinguished. It often occurs that a vessel will boil over and extinguish the gas, with the result that the room quickly fills with gas and serious harm may result. It also frequently happens that the gas supply may be shut off at an outside point and when again turned on the burner will permit the gas to escape.

40 I have therefore provided a device which is positioned adjacent the burner so that a portion of the flame contacts the device and as soon as the burner is lit the gas cock will remain in open position. However, immediately upon the extinguishment of the flame, my device will serve to close the cock thus preventing any possibility of the escape of gas from the burner.

50 In the accompanying drawings wherein for the purpose of illustration is shown a preferred embodiment of my invention, the numeral 5 designates the top of a stove from which the customary grid has been removed so as to better expose the burner 6 and my device attached thereto.

55 At 7, I have shown a latch box supported upon the under surface of the stove as by

screws 8 and 9. This latch box is preferably rectangular in shape, and is of sufficient length to contain therein a spring 11 and a latch 12. The spring 11 has one of its ends secured as at 13 to the latch box, while its opposite end is slidably engaged as at 14 to the latch 12.

It will be noted that the latch 12 has a cross section which is less than the cross section of the interior of the box 7, the purpose 65 of which will be hereinafter described.

Secured to the bottom of the latch box is an inclined strip 16. This strip is positioned on the bottom of the latch box and toward the burner. This inclined strip 70 extends into the latch box to a point adjacent an opening 17, through which opening the nose 18 of a heat controlled element 19 passes.

75 The nose 18 is adapted to engage a notch 21 formed in the latch 12 in a manner to be hereinafter described.

The heat controlled element is preferably a curved member having one end secured as 80 at 22 to a bracket supported by arms 23 and 24. This construction leaves the end carrying the nose 18 free to move in accordance with the expansion or contraction of the heat controlled element. A cable 26 is 85 adapted to be attached to the latch 12 and extends forwardly and is in turn connected as at 27 to a segment 28, which segment is in turn secured to the gas cock 29 which has the usual handle 31.

90 The result of this construction is that when the operator turns the handle 31 of the cock 29 so as to permit gas to flow to the burner 6, the cable 26 will pull upon the latch 12 against the action of the spring 11. The latch will then ride upon the inclined strip 95 16 and assume the position shown in Figure IV^a. Assuming now that the operator ignites the gas issuing from the burner 6, the flame will contact the heat controlled element 19 which will immediately expand 100 thus forcing the nose 18 into the notch 21 of the latch. The operator can then release the handle 31 and the cock will remain in an open position. After the burner has been lit a few moments the continued expansion of the heat controlled element will force the latch toward the right of Figure IV^a and to the position shown in Figure IV^b. The purpose of this side-sliding action is that should 105 the gas become extinguished and the heat 110

controlled element commences to contract, it will move but a short distance before the ends 18 will become disengaged from the latch for the reason that the latch has 5 dropped down back of the inclined strip 16 as indicated in Figure IV^b, which will now permit the spring 11 to draw the latch to the position shown in Figure II, which will also draw upon the cable 26 and through 10 this connection to the segment 28, will shut off the cock 29.

It will thus be impossible for any gas to escape from the burner at any time when there is no flame.

15 It will of course be obvious that the flame may be lowered by the ordinary manipulation of the handle 31 without effecting the operation of my device.

It will thus be seen that I have produced a 20 device which will be simple in construction, and will accomplish all the objects herein set forth in an efficient manner.

It is to be understood that the form of my 25 invention herewith shown and described is to be taken as a preferred example of the same and that various changes relative to the

size, shape and arrangement of parts may be resorted to without departing from the spirit of the invention or the scope of the subjoined claim.

Having thus described my invention, I claim:—

In a device of the class described, the combination with a gas burner having a gas cock, a latch box positioned adjacent to said burner, a latch positioned within said latch box, a spring secured to said latch box and said latch, an inclined strip positioned within said latch box, said strip being of less width than width of latch box, a notch formed in said latch, a heat controlled element positioned adjacent to said burner and adapted to be contacted by the flame therefrom, a nose formed on said heat controlled element, said nose being adapted to extend into said latch box for the purpose of engaging said latch when said burner is lit, means for connecting the latch to said gas cock of said burner, for the purpose specified.

In testimony whereof I affix my signature.

ARTHUR R. THOMPSON.
